United States Patent Office.

B. B. HOTCHKISS, OF NEW YORK, N. Y.

Letters Patent No. 63,161, dated March 26, 1867

IMPROVED RAILWAY TRACK.

The Schedule referred to in these Letters Patent and making part of the same.

TO ALL WHOM IT MAY CONCERN:

Be it known that I, B. B. Hotchkiss, of the city of New York, and county and State of New York, have invented certain new and useful improvements in Railroad Tracks, by which I mean the rails, in combination with the supports upon which they rest, and I do hereby declare that the following is a full and exact description thereof.

I will first describe what I consider the best means of carrying out my invention, and will afterwards designate the points which I believe to be new. The accompanying drawings form a part of this specification.

Figure 1 is a side elevation of a piece.

Figure 2 is a longitudinal section of a piece.

Figure 3 is a cross-section on line S S, fig. 2.

Figure 4 is a cross-section through line T T, with the rail removed to show the ledge outside thereof.

Figure 5 is a plan view.

Similar letters of reference indicate corresponding parts in all the figures.

A A, B B, &c., are blocks of pine or other suitable wood, sawn in the forms represented, and standing with the grain vertical. C is a bed of broken stone. D D¹ is a casting, the bottom part D forming a support for the lower ends of the blocks A B, and the webs D¹ forming the lateral supports for said blocks. The upper ends of the blocks A and B may be grooved in a direction across the road, as indicated by a, in those cases where it is desired to impel the cars by animals travelling on the road between the tracks. There are holes in the base-plate D, as represented, which allow the moisture to escape into the earth. M M are the rails, of wrought iron, made in any of the approved forms, and held down by spikes, M¹, or other suitable fastenings. These rails are peculiarly supported upon the wood of the blocks A B by a ledge, D², which extends up from the webs D¹, as indicated. Those portions of the blocks A B on which the rails M are to rest are sawn down or otherwise shortened, as represented, so as to allow the upper surface of the rails M M to be flush, or nearly so, with the upper ends of the remaining blocks A B. I take care to select for these portions wood which is sound and clear, so as to possess as even a character as possible, and to maintain an elastic support for the rails for as long a period as possible. D² is the ledge of iron above referred to. It is cast on and forms a part of the main bed casting D, and extends up sufficiently above the lower edges of the rails M M to form a lateral support and prevent the same from spreading apart. In cases where it shall be necessary to adjust the width of the track so that the rails M shall be a little nearer together than the arrangement here indicated, I can apply pieces of wood, iron, or other suitable material not represented between the ledges B² and the outer faces of the rails M. Where, however, the castings D D¹ D² are made with reasonable care, there will be no necessity for any considerable thickness of such adjusting pieces. My track, as represented, is particularly well adapted for the horse rail-roads now very extensively employed in this country, where the cars are impelled by horses travelling in the space between the rails. The grooved blocks A B form an excellent foot-hold, and in order to keep this in condition for a long period, the grooves a may be filled with small stone or gravel, and the greater portion or the whole of the surface of the wood may be covered with coal tar. The interstices between the gravel may also be partially or entirely filled with tarry matter. In cases where it is desired, other sections of castings, D D¹, similarly filled with blocks, A B, may be matched against the ends of these blocks, and thus form a wide pave-ment to the street, the sections for the pavements being of various lengths and forms, and matched together in various ways, as may be desired. In such cases, or in any case, I propose to provide an extra support, when desired, under the ends of my castings D D¹ D², which may be done by a large stone, or the like, under each end, or preferably in most cases by a cast-iron plate. It will be understood that the castings D D¹ D², and their contents, are held together side by side, and that the rails are laid across their ends so as to form a continuous and uniform track. Any suitable variety of chair may be used to form an additional support at the joints or junctures of the ends of the rails, if desired. I propose in most cases, however, to employ at the joints merely a plate of thick boiler iron or of cast iron laid under the joint. In such cases I cut down the wood blocks A B so much lower at those points as is necessary to allow the introduction of this support not represented. I propose to coat the surface of the wood under the rails M with coal tar or other preserving material, to increase their durability, whether the other wood be so treated or not. Screws, spikes, or other fastenings may be

employed, if desired, to assist in holding the whole or any portion of the blocks A B firmly down in the cells or spaces between the webs D¹ D². A hook-headed spike, so applied as indicated by N, in figs. 2 and 3, and a screw, with broad and sharp threads adapted to a very strong hold on the wood, is also shown by N in the same figures. Figs. 1 and 2 show, in dotted lines, a joint which will exist in my wood portions, when, as I sometimes propose to construct the pavement, the portions of the wood which support the rails are separate from the adjacent portions. In such cases the wood immediately under the rails may lie with the grain longitudinal if preferred, and in that position will hold the fastenings better than if upright. In order to avoid any tendency (which in some instances might become an evil) to form ruts by the wheels of loaded vehicles travelling just outside of my rails, I can extend the casting D¹ beyond the rails, or can extend alternate pieces of pavements in this manner. I can also construct each piece of pavement with the joints at the ends formed obliquely so as to present no joint extending longitudinally to the line of travel. In all such cases I can make the edges D² at the proper points on each piece so as to retain the rails M in the right distances, and the ends of the castings extend beyond without involving any difficulty. I do not consider the ledges D² absolutely necessary where the rails thus pass through the pieces of pavement, because the high blocks A B, or portions thereof, adjacent to the rails on their outer sides, perform analogous functions. But I propose to employ the cast ledges D² in all cases where it is deemed important to maintain the rails exactly in place without a possibility of spreading.

I do not claim supporting the rails of railroads upon thin supports of wood intervening between them, and chairs or the like metal supports, nor do I claim supporting the rails upon metal sleepers, extending across the track, except when the sleeper forms also a support for a wood pavement, as specified; but having now fully described my invention, with what I consider the best means of applying it in practice, what I claim as my invention, and desire to secure by Letters Patent, is as follows:

I claim the construction and arrangement of a street-railway track in sections consisting of cast-iron cellular base-plates, in which are inserted blocks of wood fitting therein, with the rails arranged upon the outer sides of said track, and held in position as herein described, the whole being so constructed and arranged as herein set forth.

B. B. HOTCHKISS.
